UNITED STATES PATENT OFFICE.

HENRY F. DUNN, OF ANDERSON, INDIANA.

DESIGN FOR AN ADVERTISING CHANGE-TRAY.

43,525.

Specification for Design.

Patented Feb. 11, 1913.

Application filed July 26, 1912. Serial No. 711,737. Term of patent 7 years.

To all whom it may concern:

Be it known that I, HENRY F. DUNN, a citizen of the United States, residing at Anderson, in the county of Madison and State of Indiana, have invented a new, original, and ornamental Design for Advertising Change-Trays, of which the following is a specification.

In the accompanying drawings, Figure 1 is a plan view of the advertising change tray embodying my new design and Fig. 2 is a vertical section.

I claim:

The ornamental design for an advertising change tray, as shown.

HENRY F. DUNN. [L. S.]
